UNITED STATES PATENT OFFICE.

HARMON F. ACKERMAN, OF CLEVELAND, OHIO.

SCRUBBING-MACHINE.

937,353.

Specification of Letters Patent. Patented Oct. 19, 1909.

Application filed August 4, 1908. Serial No. 446,887.

To all whom it may concern:

Be it known that I, HARMON F. ACKERMAN, a citizen of the United States, residing at Cleveland, in the county of Cuyahoga and State of Ohio, have invented certain new and useful Improvements in Scrubbing-Machines, and do declare that the following is a full, clear, and exact description of the invention, which will enable others skilled in the art to which it appertains to make and use the same.

My invention relates to an improvement in scrubbing machines, and the invention consists in the construction and combination of parts, substantially as shown and described and particularly pointed out in the claims.

In the accompanying drawings, Figure 1 is a side elevation of the machine. Fig. 2 is a plan view of the drain trough about the scrubbing brushes or rolls. Fig. 3 is a plan view of the scrubbing rolls and of a portion of the driving means therefor partially in section. Fig. 4 is an enlarged longitudinal sectional elevation of the machine, and Fig. 5 is an enlarged section or portion of the endless elevator which carries away the dirty water from the drain trough.

As thus shown the machine, or rather the scrubbing parts of the machine, are power driven from an electric or other motor M, mounted on the rear of the machine, and the machine is handled on the floor by means of the handle-bar, tongue or pole P, which may be single or divided so as to extend to the corners of main frame F, and with which it is rigid. It is to be observed, however, that the said bar or part P is affixed to the rear of the machine so as to push the machine over the floor rather than draw it, and two carrying wheels W are loosely mounted on shaft S and adapted to sustain the weight of the motor, while the bulk of frame F and all the parts thereon is sustained by transversely disposed scrubbing brushes or rolls B and B'. The said brushes are cylindrical in shape, and have a length equal to the full width of the main frame and are provided with bearings in the lower portions or legs 2 of the said frame. Both brushes are driven alike from motor M by sprocket chain m running over sprocket wheel n fixed on power driven shaft S, and thence from sprocket wheel 3 on said shaft and chain C thereon operatively engaging the smaller sprocket wheels b and b' respectively of the

respective scrubbing rolls B and B', the idler I serving as a take-up for the said chain.

The rolls B and B' are arranged to work inward toward each other, so that as they travel over the floor together they sweep one toward the other, and while roll B runs over the unscrubbed portion and throws the water and dirt inward toward roll B', the roll B' catches up these sweepings and carries them forward toward roll B, so that the two brushes play against each other in their work and while both work on a thoroughly moistened surface they can do more effective work in this way than if they rotated in the same direction, as is obvious. It is planned that they shall also coöperate in gathering up the dirt laden water and deposit the same in a trough provided for this purpose and the reverse rotation of the rolls contributes to this end. Hence I have provided a frame shaped trough D about the said rolls, all portions of which are adapted to catch water carried up or over by the rolls and which trough lies close to the rolls at their sides and ends and is especially provided with a middle portion d of greater width than the sides thereof and which receives the water deposited in the other portions of the said trough as well as that thrown directly thereinto by the brushes and from which the water is lifted to the basin or receptacle E above and passes thence by spout 5 into tank T which is separate and removable.

The lift mechanism comprises endless chains 6 and trough shaped brackets 7 fixed at their ends to said chains and having a length equal approximately to three-fourths of the said trough frame D, more or less. The said chains 6 run over sprocket wheels 8 and 9 top and bottom respectively of the upright frame or posts 10, rigid with the main frame, and power is applied to said endless chain and bucket carrier by a chain or belt 12 from sprocket wheel or sheave 13 on shaft S to wheel 14 on shaft 15 which carries the sprocket wheels 8 above.

It is seen from the foregoing that buckets 7 dip and fill in central trough d, and the plan is to gather up at least the bulk of the scrubbing water after it has done its work and which is played back and forth between rolls B and B', and the more thus gathered up the better. The complete operation is such as to leave the floor practically clear of water as it is passed over by the machine, and what remains can easily be dried off in

some other way. When tank T is filled it can be removed by hand and emptied.

It is to be understood from the foregoing that the work of the machine is performed by power, including removal from the floor of the water used by the machine, and all that the operator has to do is to traverse the machine over the floor such as he would a lawn mower, and this is easily done. If desired to reverse the machine he can tilt it on its wheels W so as to lift the scrubbing rolls entirely from the floor, but while at work the entire front weight is permitted to rest down upon the rolls and thus contribute to their efficiency.

Suitable shields or covers 16 are provided over the rolls B and B', and which are inclosed about their vertical side edges by the vertical flanges 17 of the trough or draining member D, and the said draining or trough member is suspended from main frame F by screw rods 20, or their equivalent, thus being made removable for cleansing and also permitting adjustment of the trough member in respect to the brush rolls and the buckets on chains 6.

What I claim is:—

1. A scrubbing machine comprising a pair of scrubbing rolls and means to drive said rolls inward toward each other at the floor, in combination with a drain trough entirely around both rolls and having a branch extending between said rolls open at its ends to communicate with the portion of said trough at the ends of the rolls.

2. A scrubbing machine comprising a pair

of reversely rotating scrubbing rolls, an endless trough about the outside of said rolls having a branch between its sides open across its top between said rolls and communicating with the sides thereof, and a lifting mechanism adapted to dip into said branch and raise the wafer therefrom, and hoods over the outer portion of said trough.

3. A floor scrubbing machine comprising a main frame and a pair of scrubbing rolls and power connections to drive the same, in combination with a rectangular trough extending front and rear and across the ends of both rolls and having a branch portion between the rolls to receive the water lifted by the rolls and open to the sides of the trough at its ends, and means removably supporting said trough from the main frame about said rolls.

4. A scrubbing machine having a main frame, a set of scrubbing rolls therein, an endless trough detachably suspended from said main frame and extending along the outer sides and ends of said rolls and an uncovered branch thereof between the rolls in open communication with the sides of said trough, and hoods for said rolls mounted on said trough to cover the same and adapted to discharge water dashed thereon within said trough.

In testimony whereof I sign this specification in the presence of two witnesses.

HARMON F. ACKERMAN.
